UNITED STATES PATENT OFFICE.

HARRY RUBENSTEIN, OF BROOKLYN, NEW YORK.

APPARATUS AND METHOD FOR PRODUCING KNITTED FABRICS.

Application filed June 13, 1925. Serial No. 36,914.

The invention relates to knitted fabrics and the method of and apparatus for producing the same.

The principal object of the invention, generally stated, is to provide means for and a method of making a knitted fabric possessing certain characteristic features in the arrangement and location of the loops or wales whereby an unusual and highly attractive 10 appearance will be obtained.

Another object of the invention is to provide, in a circular knitting machine, a novel combination and arrangement of needles, actuating cams therefor and other associated structural elements which will effect the peculiar loop or wale formation producing a fabric having the desired characteristics.

A more specific object of the invention is to provide a method of knitting involving 20 means including different sets of needles, the needles in the different sets operating in alternation and having different paths of movement whereby to provide or form loops or wales all or certain of which are inter-linked to make the fabric.

A still more specific object of the invention is the provision of a knitting method and means for carrying it out including sets of needles having their general features in 30 common but having separate operating means formed as cams, the needles of the different sets having long and short butts, respectively, coacting with the different cam elements, the long and short butt needles being 35 arranged selectively in individual alternation or in alternate groups.

A further object is the provision of a knitting method and means for carrying it out including sets of alternately operable needles having the usual beards automatically closed by pressers or beard closers at certain times to effect interlinking of the loops or stitches, the means and method involving the omission of the beard closing means at a certain 45 point or points whereby at periodic intervals a thread or threads will be simply laid instead of being knitted whereby a characteristic appearance in the finished fabric will be obtained.

Practically considered, the object of the invention is to provide a method of and means for knitting fabrics known commercially as "twill sheen" and "twill sheen crepe," which fabrics are protected by a 55 duly registered trade mark.

To the attainment of the foregoing ob-

jects and advantages the invention consists preferably in the method and the means for carrying it out to be hereinafter more fully described and claimed and illustrated in the 60 accompanying drawings wherein:

Figure 1 is a diagrammatic plan view of a circular knitting machine embodying means for producing one form of fabric.

Figure 2 is a magnified view of one type 65 of fabric,

Figure 3 is a magnified view showing a modified form of fabric,

Figure 4 is a vertical section through a portion of the knitting machine illustrating 70 certain necessary mechanical features thereof,

Figure 5 is a view showing two sections of the cam mechanism for moving the needles for producing the fabrics shown in Figures 75 2 and 3,

Figure 6 is a horizontal section on substantially the line 6—6 of Figure 5, certain elements being shown in plan,

Figure 7 is a cross section on the line 7—7 80 of Figure 5,

Figure 8 is a section on the line 8—8 of Figure 5.

Referring to the drawings in detail, I have illustrated, more or less diagrammatically, a 85 portion of a circular knitting machine of a well known type. Only such parts are illustrated as are necessary for an understanding of the present invention. Machines of this type include a stationary table 1 above which 90 is supported, as by brackets 2, a stationary ring 3 upon which are mounted segmental or arcuate plates 4 which, together, constitute a circular ring. Suitably supported with respect to the table 1 is the rotary head 5 travelling within the confines of the plate members 4 and adjacent the inner periphery of a ring 6 stationarily mounted with respect to the table. The head 5 carries the needles which cooperate with cam devices carried by 95 the ring 6.

In carrying out the present invention I make use of two sets of needles, those of one set being designated by the numeral 7 and having long butts 8 and those in the other set being designated by the numeral 9 and provided with short butts 10. Except in the matter of the length of the butts the needles are all similar and are provided at their upper ends with the usual beards 11 which 105 catch the threads for carrying out the knitting action. Operating between the succes-

sive needles are the usual radially movable sinkers or pressers 12 having projections 13 thereon engaged within cam grooves 14 of such formation as to control the outward and inward movement. Machines of this type are further provided with beard closers 15 for the purpose of closing the beards 11 so that they may enter and pass through the loops of a previously made row. In actual practice these beard closers are held in place by a circular coil spring 16 which surrounds the head 5 and which operates to hold the beard closers out of operative relation to the needles. It is furthermore customary to provide cams 17 located at intervals for the purpose of lining up and retracting the beard closers 15 at points near and in advance of the knitting points, at which latter mentioned points are provided cams 18 for projecting the beard closers into operative relation to the needles so that they will function to close the beards as the needles move downwardly in making the loops or stitches. When the machine is in operation all of the needles of course turn with the head 5, the needle butts being engaged by cam means carried by the ring 6 for moving the needles upwardly and downwardly at the proper intervals.

For producing the fabric shown in Figure 2, I arrange the long and short butt needles 7 and 9 in alternation and provide a peculiar cam mechanism cooperating with the butts thereof for effecting knitting with the two sets of needles in alternation. Referring to Figure 1 it will be observed that the machine is designed to knit with eight threads 19, 20, 21, 22, 23, 24, 25 and 26, which threads are led from any suitable source and brought through suitable guides 27 and 28. It will be observed that the number of threads agrees with the number of segments or sections and that each segment has a knitting point located at the cam 18. The knitting points for the threads 19 to 26 are indicated at 29, 30, 31, 32, 33, 34, 35 and 36 respectively. In the carrying out of the method the long butt needles knit at the points 29, 31, 33 and 35 while the short butt needles knit at the points 30, 32, 34 and 36. While the long butt needles 7 are knitting, the short butt needles 9 are idle, the wales or loops formed being in alternation to define or produce the particular fabric disclosed.

In order to effect the necessary needle movement I provide cam mechanism which includes sections indicated generally by the numerals 37 and 38 arranged in alternation, the number of sections corresponding to the number of threads. The sections 37 are located at the points where the short butt needles knit whereas the sections 38 are provided for operating the long butt needles. The section 37 is shown as including a cam

39 having an inclined upper face or shoulder 40 upon which ride the long and short butt needles. To illustrate the action, the path of movement of the short butt needles is indicated by the dotted line 41 and the path of movement of the long butt needles by the dash line 42. Located above and extending beyond the cam 39, with respect to the path of movement of all the needles, is a cam 43 having a shoulder 44 curved downwardly as shown at 45 for the purpose of directing the short butt needles to a third cam 46 which is located at the knitting point 30, 32, 34 or 36. The cam 43 has a downwardly inclined lower shoulder 47 located in the path of movement of the long butts so as to move the long butt needles downwardly out of the way while the short butt needles are knitting. Below the cams 43 and 46 is a cam 48 having a ledge 49 along which the long butts travel. The cam 46 has an inclined surface or shoulder 50 which leads downwardly from the curved end 45 of the shoulder 44 and which is engaged by the short butts for moving the short butt needles downwardly and causing them to perform their knitting action while the long butt needles remain in lowered and inoperative position.

The section 38 includes a cam 51 having an inclined shoulder 52 leading upwardly from a point below the cam 46 and located in such position and projecting to such an extent as to be engaged by the long butts. The cam 51 is provided with a ledge 53 upon which will engage and ride the short butts of the needles which have knitted at the cam 46. The section 38 further includes a cam 54 corresponding exactly to the cam 46 and similarly provided with a downwardly inclined shoulder 55 and located at the point 105 where the long butt needles knit. In the section 38 is a cam 56 having a projecting shoulder 57 spaced from the upper edge or shoulder 58 of a cam 59. After riding up the inclined shoulder 52 the long butts are carried along between the shoulders 57 and 58 to the shoulder 55 at which point the long butt needles are moved downwardly so as to perform their knitting action while the short butt needles travelling along the ledge 110 53 and along an alining ledge 60 on the cam 59 will remain in lowered and consequently inoperative or idle position. As stated above, the sections 37 and 38 alternate, the cam 39 of each section 37 being positioned 115 to be engaged by all the needle butts after completion of the knitting action of the long butt needles as they pass under the cam 54. From the above it will be seen that at certain periods all the needles are raised while at other periods the long and short butt needles are alternately lowered to effect knitting, in each instance one set or the other remaining idle.

In the operation, it will be seen that when 130

the head 5 carrying all the needles 7 and 9, the beard closers 15 and the sinkers or pressers 12 is rotated, the beard closers are drawn back away from the needles by the cams 17 located in advance of the knitting points at which are located the cams 46 and 54 for moving the short and long butt needles, respectively, downwardly. The exact manner of thread treatment or handling at the starting 10 of the machine is the same as usual and assuming that the machine has been operating to a sufficient extent to start the fabric properly, it will be seen that when the butts 9 of the short butt needles 7 come into engagement with the inclined edge 50 of the cam 46 of the sections 37 the short butt needles are moved downwardly as indicated by the dotted line 41 in Figure 5. In advance of this point the long butt needles are moved downwardly as indicated by the dash line 42 in Figure 5 and are in inoperative position. As the short butt needles 7 are moved downwardly the beard closers 15 are forced toward the needles by engagement 20 with the cams 18. The threads 26, 24, 22 and 20 are of course engaged within the beards of the short butt needles and when these needles are moved downwardly the beards will engage the closers 15 and be closed thereby so that the beards, carrying the threads, will enter and pass through the loops 20^a, 26^a, 24^a and 22^a, respectively, of the previously knitted threads. Upon then moving upwardly the knitted loops are cast 30 off from the needles and new loops are formed. The sinkers or pressers 12 of course operate in a well known manner. The threads 25, 23, 21 and 19 engaged by the long butt needles 8 are knitted in exactly the same manner except that the long butt needles are operated by engagement with the inclined edges 55 of the cams 54 in the sections 38, the upward and downward movement resulting in the formation of the loops 25^a, 23^a, 21^a and 19^a. Referring to Figure 40 2 it will be seen that all the loops made by each short butt needle are interlinked and that all those made by each long butt needle are similarly interlinked. Owing to the fact that the long and short butt needles are arranged and operate in alternation, the portions of the threads between the loops formed by the long butt needles will overlie the interlinking loops made by the short butt needles, the intermediate portions of the threads knitted by the short butt needles similarly overlying the interlinking loops formed by the long butt needles. As a result the loop connecting portions of the threads knitted by the different sets of needles are arranged in alternation or are staggered as clearly shown to provide a distinctive pattern.

In forming the modified fabric disclosed in Figure 3 one of the beard closer operating

cams 18 is removed so that one of the threads will be simply laid in the fabric instead of being actually knitted with the adjacent threads. For the sake of illustration let it be assumed that the beard closer at the knitting point 33 has been removed. This one is selected arbitrarily as it is of course obvious that any other one may be removed to obtain the same effect. If the beard closing cam 18 at the point 33 be removed it is obvious that the laid or unknitted thread will be the one indicated at 23, all the other threads being knitted together in exactly the same manner as above described. Owing to the removal of the beard closing cam at this point 70 it will be seen that when the long butt needles engaging the thread 23 are moved downwardly by the engagement of their butts with the cam 54 located at the knitting point 33 there will be nothing to close the 80 beards and they consequently remain open and cannot enter and pass through the loops 25^a as occurs at all the other knitting points. As the thread 23 is not knitted at this point 85 it follows that upon the upward movement 90 of the needles a loop 23^b is formed lying upon or against the loop 25^a. When the thread 21 is then knitted in, the needles carrying it and having their beards closed at the knitting point 31 will enter and pass 95 through the loops 25^a and also the loops 23^b, both being then cast off into the fabric to form the particular design shown in Figure 3.

From the foregoing description and a 100 study of the drawings it will be seen that I have provided a fabric forming method and means therefor embodying certain known principles of design but involving an arrangement of operatively related elements 105 which will produce a fabric possessing certain highly desirable characteristics in the matter of pattern.

While I have shown and described the preferred embodiments of the invention, it 110 should be understood that the detailed steps in the method and the specific arrangement, location and correlation of the parts is merely for illustrative purposes as I reserve the right to make all such changes and modifications as will not depart from the spirit of the invention or the scope of the claims hereunto appended.

Having thus described the invention, I 115 claim:

1. The method of producing a knitted fabric consisting in utilizing different sets of needles having a certain fixed relation and knitting a plurality of threads with the different sets in alternation whereby alternate 120 threads will be linked together at points in staggered relation to the points of knitting of the other threads, and omitting the knitting action on one of the threads whereby it will be simply laid in with the adjacent 125

130

thread for producing a distinctive pattern in the fabric.

2. In a knitting machine, the combination of needles having long and short butts and arranged individually in alternation, and a cam ring including a plurality of sections each having a groove therein receiving all the butts, the groove having surfaces acting upon all the butts and having other surfaces

acting only upon the short and long butts 10 respectively at intervals, the needles having beards, and beard closing means at all of the sections but one, the omission of the beard closing means at the one section preventing knitting of one thread whereby said thread 15 will be laid in with an adjacent thread.

In testimony whereof I affix my signature.

HARRY RUBENSTEIN.
